ARNOLD GULDEMANN, OF PATERSON, NEW JERSEY.

HAND-THREADING SHUTTLE.

1,029,289.

Specification of Letters Patent. Patented June 11, 1912.

Application filed September 7, 1911. Serial No. 648,130.

To all whom it may concern:

Be it known that I, ARNOLD GULDEMANN, a citizen of the United States, residing at Paterson, in the county of Passaic and State 5 of New Jersey, have invented certain new and useful Improvements in Hand-Thread- 60 ing Shuttles, of which the following is a specification.

The principal object of this invention is 10 to provide a shuttle of the so-called hand-threading type which shall be free of the slit-forming tongue or the like, now commonly employed in effecting the introduction of the thread to the thread-guiding eyelet. 15 in the operation of threading the shuttle, such tongue being known to possess the disadvantage that it is likely to and often does catch in the warp in the movements of the shuttle back and forth through the shed. 20 Another object of the invention is to incorporate a tension means in a removable structure forming a part of the hand-threading means.

In the accompanying drawing, Figure 1 25 is a plan view of the improved shuttle; Fig. 2 is a side elevation of that end-portion of the shuttle to which the subject of the present invention relates; Fig. 3 is a similar view, showing the shuttle partly in section 30 on the line $w-w$ of Fig. 1 or $w'-w'$ of Fig. 6; Fig. 4 is a sectional view on the line $x-x$ of Fig. 2; Fig. 5 is a sectional view on the line $y-y$ of Fig. 2; Fig. 6 is a sectional view on the line $z-z$ of Fig. 1; and, Fig. 35 7 shows a removable part of the shuttle removed and in side elevation.

a is the shuttle-body having the shuttle cavity b for the filling c and the means d for supporting the filling. An extension e 40 of this cavity extends toward one end of the shuttle and is formed with the opposed grooves or ways e' (Fig. 6). Fitted into the side wall of the shuttle-body a and affording communication between the extension e 45 of the cavity and the exterior is a filling-guiding eyelet f of usual form except that it has an upwardly opening slit g .

Referring to Figs. 1 and 3 to 7, h is a 50 metallic plate which occupies the extension e of the cavity, standing in a vertical plane at that side of the cavity which adjoins the eyelet f . This plate has two angularly disposed walls i i' projecting therefrom, each wall having a projecting toe j and the plate 55 having an oppositely projecting rib k , the said toes and rib being adapted to enter the

grooves e' when, in the assembling of the plate with the shuttle-body, the plate (having been admitted to the cavity b) is forced into the extension e of said cavity. The 60 plate is formed with a lateral overhang m and from the free end of said overhang backwardly at an incline a slit n (preferably terminating in an eyelet o) is formed in the plate, thus producing a tongue p . 65 The eyelet o coincides with the filling-guiding eyelet f when the parts are assembled. The walls i i' are formed with coinciding slits q q' inclined downwardly toward the plate h and terminating in the eyelets r r' . 70 Secured to the wall i' in any suitable manner is a wire filling guard s crossing the slit q' and serving to retain the thread in the slits q q' once it is entered into the same. It will be observed that the tongue p projects away from the supply of filling and past the thread eyelet f . Through the side wall of the shuttle occupied by the filling eyelet f and back of the same relatively to the free end of the tongue p an aperture t 80 is formed, the same communicating with the slit g of the eyelet f by the angular slit u formed in said side wall of the shuttle. In the walls i i' is arranged a screw pin v on which is fulcrumed a tension plate w normally held flatwise against the plate h by a spiral spring x coiled about the pin v and having one end engaging the tension plate and the other secured to the pin. The filling is normally held pressed between the 85 tension plate and the plate h , being thereby kept under tension. By adjusting the pin v the degree of tension may be varied as will be obvious. Once the plate h has been introduced into the extension e of the cavity b in the manner described, it may be held in place by the screw pin y , or in any other suitable manner. 90

In threading the shuttle, the weaver passes the filling first between the guard s 100 and the wall i' , until the filling will be admitted to the slits q q' . The filling is then entered into said slits, having first forced back the tension plate so that the filling will extend between the same and the plate h . The filling is then looped under the tongue p which on a view to Fig. 1 will be seen to stand clear of the walls of the extension e of the cavity b . The free end of the filling, now looped under the tongue, 105 passing through the eyelet o , and extended back from said eyelet between the plate h 110

2
and the wall of the shuttle in which the eyelet *f* is arranged, is then passed through the aperture *t* (made sufficiently large for the purpose) and, having then been entered into 5 the slit *u*, it will find its way into the filling-guiding eyelet *f*. Once in the eyelet *f* it is retained therein by the eyelet *o*. It will be observed that the tongue *p* is sufficiently depressed so as to effectively sheath 10 it against catching in the warp when the shuttle is in use. To facilitate looping the filling under the tongue the material of the body of the shuttle around the extension *e* of the cavity *b* is recessed as at *z*.
15 Having thus fully described my invention, what I claim as new and desire to secure by Letters Patent is:—

1. In a shuttle, a filling-tension device including two coacting filling-gripping members having relatively broad filling-gripping faces bearing flatwise against each other and each extending substantially vertically, one of said members being elastically held against the other and pivoted on 20 a substantially horizontal axis below said gripping faces, the space formed between said members when the pivoted member is moved out of contact with the other member

having an unobstructed downwardly open entrance thereto whereby to admit the filling 30 between said members by a downward movement thereof, substantially as described.

2. In a hand-threading shuttle, the combination of a shuttle body, a supporting part arranged therein and having spaced lateral projections formed with filling-guiding slits and also having a filling-holding tongue projecting toward one end of the shuttle body, means, carried by said part, for retaining the thread in said slits, and a spring actuated tension member arranged 35 between said projections and normally held in filling-gripping relation to said supporting part, said tension member being arranged substantially vertically, pivoted at or near its lower end and having its upper end-portion exposed for manual engagement.

In testimony whereof I affix my signature in presence of two witnesses.

ARNOLD GULDEMANN.
